(57) **CLAIM**

I claim the ornamental design for a hex bit tool, as shown and described.

DESCRIPTION

FIG. 1 is a perspective view of a hex bit tool, showing a first embodiment of my new design;

FIG. 2 is a top plan view of FIG. 1, the bottom plan view being a mirror image thereof;

FIG. 3 is a left-side elevational view of FIG. 1, the right-side elevational view being a mirror image thereof;

FIG. 4 is a front elevational view of FIG. 1, the rear elevational view being a mirror image thereof;

FIG. 5 is a cross-sectional view of FIG. 1, taken generally along lines 5-5 of FIG. 3;

FIG. 6 is a perspective view of a second embodiment of my design;

FIG. 7 is a top plan view of FIG. 6, the bottom plan view being a mirror image thereof;

FIG. 8 is a left-side elevational view of FIG. 6, the right-side elevational view being a mirror image thereof; and,

FIG. 9 is a cross-sectional view of FIG. 6, taken generally along lines 9-9 of FIG. 8.

The broken lines illustrating a bit in FIGS. 1 and 6 are directed to environment and form no part of the claim. All other broken lines in the figures illustrate unclaimed portions of the design.
